UNITED STATES PATENT OFFICE.

EDGAR B. HOOVER, OF PASCO, WASHINGTON.

ROTARY PUMP.

1,414,512.

Specification of Letters Patent.

Patented May 2, 1922.

Application filed February 5, 1921. Serial No. 442,608.

To all whom it may concern:

Be it known that EDGAR B. HOOVER, a citizen of the United States, residing at Pasco, in the county of Franklin and State of Washington, has invented certain new and useful Improvements in Rotary Pumps, of which the following is a specification.

This invention relates to rotary pumps and has for its object to provide a means 10 for lifting water or other liquids.

A further object is to provide a means for lifting water or the like having an enlarged base and a restricted outlet whereby a greater suction may be obtained and where- 15 by the liquid is given a gradual increase in velocity.

A further object is to provide a means for lifting water and the like which is equally efficient whether placed vertically or inclined.

20 A further object is to provide a means for properly journalling the lifting elements and for preventing the ingress of air to the cylinder with detrimental effect.

With these and other objects in view ref- 25 erence is now had to the accompanying drawings, in which—

Fig. 1 is a vertical sectional view of the pump;

Fig. 2 is a plan view of the base;

30 Fig. 3 is a sectional view of the base and inlet;

Fig. 4 shows pump in an inclined position;

Fig. 5 is a sectional view of the bearing spider on the line 5—5 of Fig. 6;

35 Fig. 6 is a plan view of the spider bearing;

Fig. 7 is a partial sectional view of the foot bearings; and

Fig. 8 is a sectional view of the journal in the hollow shaft.

40 Having reference to the drawings like numerals refer to like parts throughout and the numeral 1 refers to the cylinder which is conical in shape and is composed of an enlarged base 2 having inlets 3 therein, a re- 45 stricted outlet 4, and tapering side walls 5.

Within the cylinder is a conical shaped conveyor corresponding to the shape of the cylinder which is ground to frictional contact with the base and side walls thereof.

50 To the cylinder and in prolongation thereof is suitably attached a discharge pipe 7, and within this pipe is a helical conveyor 8 which is also ground to frictional contact with the side walls of the discharge pipe.

55 The conveyors 6 and 8 respectively are rotated in opposite directions by means of

the gearing 9, 10, 11 and 12 and the belt 13, (or pulley 14) through the hollow shaft 15 and the solid shaft 16.

It is obvious that the conveyors must operate with precision and the bearings therefor must interfere with the flow of the liquid as little as possible, therefore the upper and exposed bearings are of peculiar construction, while the lower journals being in the base of the cylinder are of the usual type as greater rigidity will naturally be maintained here. The bearing 17 for the hollow shaft being of the nature of a packing nut 18 through which the hollow shaft extends. 70

Within the hollow shaft is also a journal 19 in which the solid shaft 16 rotates.

As there is a liability of an air leakage through the bearing in the hollow shaft which would be detrimental to the action of 75 the pump, I have provided an orifice 20 in the hollow shaft 15 through which the liquid contents of the pump may cover and surround the journal and thus prevent an air leakage at this point. 80

The upper bearings are exposed and the bearing 21 guides the conveyor 6 while the bearing 22 guides the conveyor 8. As both of these are alike they will be explained, as one and with reference to Figs. 6 and 5. 85

23 refers to the race of the bearing which is attached to the side walls in any suitable manner, with the balls 24 of the usual type, and with the inner portion or cone 25 forming with the arms 26 and hub 27 a spider 90 bearing.

The upper edge 28 of the conveyor is attached to one arm of the spider and the two rotate together.

To prevent either shaft from dropping I 95 provide foot bearings 29 and 30, the foot bearings in turn being supported by a suitable frame work 31.

In operation the conveyors are operated by any suitable prime mover and from the 100 intake or discharge end of the pump as shown in Fig. 1 and Fig. 4, Fig. 1 also showing the inlet or suction pipes 3 which project downward to enter the liquid, and that of Fig. 4 showing the whole base of the 105 pump submerged.

In driving the pump from the discharge end the power is communicated to the solid shaft 16 and through this shaft and the gears 9, 11 and 12, and gear 10, to the hollow 110 shaft 15.

As these two shafts and with them the

conveyors, are rotated, the lower edge of the conveyor 6 passes over the floor of the base 2 and over the open ends of the inlets 3 in the direction of the horizontal arrow shown in 5 Fig. 3; the rapid movement of the conveyor creates a partial vacuum over the inlets resulting in the liquid flowing into the cylinder in the direction of the curved arrow shown in Fig. 3.

10 As the liquid rises in the cylinder a portion enters the orifice 20 and seals the journal 19, the body of the liquid now rises to and through the restricted outlet with a slight whirling motion and is taken up by 15 the helical conveyor 8 which, traveling in the opposite direction to the whirling liquid cuts into it, as it were, and through its velocity raises the liquid up the incline of the blade of the conveyor.

20 Now the larger lower portion of the conical shaped conveyor 6, having a greater relative area than the upper portion, is utilized for the purpose of suction as it is obvious that with the same velocity the larger portion 25 will create the greater vacuum; and by restricting the outlet the volume of liquid passes therethrough with a slight resistance which with the reaction of the upward movement will tend to a greater density of 30 the liquid which will aid to form a more perfect vacuum.

The inlet 3 and the outlet 32 is in a continuous line with that of the pump, i. e. there 35 are no bends in either; thus the friction due to curved pipes, which in the discharge end would cause a back pressure, is eliminated.

Having thus described my invention, I claim—

1. In a rotary pump, the combination of 40 a conical shaped cylinder, a conical shaped conveyor within said cylinder, a discharge pipe in prolongation of and attached to said cylinder, a conveyor within said discharge pipe, a means for rotating said conveyors in 45 opposite directions on a hollow and solid shaft respectively, a means for forming an airtight journal in said hollow shaft to prevent the ingress of air to said cylinder, a means for journalling said conveyors against 50 the side walls of said cylinder and discharge

pipe, and foot bearings supporting said shafts.

2. In a rotary pump, the combination of a conical shaped cylinder frustumed to connect with a discharge pipe, a conical shaped 55 conveyor within said cylinder and ground to operatively engage the base and side walls thereof, a discharge pipe, a helical conveyor within said discharge pipe and ground to frictional contact with the side walls thereof, a means for rotating said conveyors in opposite directions on a hollow and solid shaft respectively, a means for forming an air tight journal in said hollow shaft, and a liquid seal therefor to prevent the ingress of 60 air to the cylinder, a means attached to and rotatable with said conveyors for journaling said conveyors against the side walls of said cylinder and discharge pipe respectively, foot bearings supporting said shaft 65 without the pump, and a suction pipe attached to said cylinder and projected downward therefrom in a straight line to form a straight continuous passage from the intake to the discharge.

3. In a rotary pump, in combination, a conical shaped cylinder, a conical shaped conveyor within said cylinder and ground to frictional contact with the base and side walls thereof, a discharge pipe, a helical 80 conveyor within said discharge pipe, a means for rotating said conveyors in opposite directions on a hollow and solid shaft respectively, a means for forming an air tight journal in said hollow shaft consisting 85 of an orifice in said hollow shaft through which the liquid contents of the pump may flow to surround said journal, a spider bearing attached to and rotatable with each of said conveyors and having its bearing 90 against the side walls of said cylinder and discharge pipe respectively, and foot bearings supporting said shafts without the pump, and a suction pipe attached to said cylinder and projected downward therefrom 95 in a straight line to form a straight continuous passage from the intake to the discharge.

In testimony whereof I affix my signature.
EDGAR B. HOOVER.
